UNITED STATES PATENT OFFICE.

MAX PUGATSKY AND ROBERT D. VON RENTSCH, OF NEW YORK, N. Y.

GARMENT.

1,396,462.

Specification of Letters Patent.

Patented Nov. 8, 1921.

Application filed December 17, 1919. Serial No. 345,542.

To all whom it may concern:

Be it known that we, MAX PUGATSKY and ROBERT D. VON RENTSCH, both citizens of the United States, and residents of the borough 5 of Manhattan, city, county, and State of New York, have invented an Improvement in Garments, of which the following is a specification.

This invention relates to garments and 10 more particularly to the edging and lining construction of a garment which may be employed in edging coats, vests, trousers, skirts or any other garment, the object of the invention being to employ an edging or 15 braid member which preferably has an edge rib and connecting the same, together with a lining, to the edge of the garment in such a manner that the seams by which the edging and the lining members are connected to 20 the garment are not visible, as will be hereinafter more particularly described.

In the drawing: Figure 1 is an elevation and partial cross section illustrating the inner edge portion of the garment in which 25 our invention is incorporated.

Fig. 2 is an enlarged cross section on line 2—2, Fig. 1.

Fig. 3 is a fragmentary cross section illustrating a modified form of the invention, 30 only that portion being shown wherein the construction shown in Fig. 2 is modified.

Fig. 4 is also a fragmentary cross section illustrating a further modification of the invention, only that portion being shown 35 wherein the construction shown in Fig. 2 is modified, and

Fig. 5 is a plan of a form of the lining in which the braid or beaded member is attached thereto before being secured to the 40 fabric of the garment.

Referring to the drawing and particularly to Figs. 1 and 2 thereof, in carrying out this invention together with the fabric of which the garment is made, this fabric being indicated at 10 and having an inturned edge 11, we employ a lining which is composed of a 45 stiffening member 12 made of canvas, duck, or any other similar material and provided with a suitable covering, as hereinafter described, together with a braid or edging which is connected to the fabric of the garment and the lining as also hereinafter described.

As illustrated in these figures, the lower 55 edge of the stiffening member 12 is provided

with a cover 13 and also with the lining member proper as indicated at 14. This lining member proper includes a skirt 15 and a loop 16 and is sufficiently wide to extend beyond the opposite edge of the stiffening member. The stiffening member 12, together with the cover 13 and the skirt portion 15 of the lining are secured together by a line of stitching indicated at 17, the loop member 16, as will be understood, being 60 formed to cover this line of stitching 17 so that the same is not visible from the inner side of the garment, the loop 16 being formed by turning back the lining member 14 over the stitching after these parts have 70 been so connected.

The braid or edging member preferably comprises a body portion 18 and an edge bead 19, shown in the drawings as a finished edge of a braid, but it is to be understood that other forms of edging members might readily be used, such as a doubled piece of material which may or may not have a cord passed between the doubled portions of the same to form an enlarged edge such as is 80 shown at 19. This braid is secured in position by placing the same on the fabric of the garment and placing the overlying edges of the lining 14 and the stiffening member 12 on the braid and connecting these parts 85 by a line of stitching indicated at 22. When so connected, the fabric 10 is overturned so as to provide the inturned end 11 thereof, and the stiffening member 12 and the lining member 14 are also overturned so as to provide 90 the inturned end 20 of the lining member 14 and the inturned end 21 of the stiffening member 12, which, as will be understood, entirely incloses and conceal the line of stitching 22 by which these parts are connected.

Referring to the drawing and particularly to Figs. 1 and 2 thereof, in carrying out this invention together with the fabric of which the garment is made, this fabric being indicated at 10 and having an inturned edge 11, we employ a lining which is composed of a 45 stiffening member 12 made of canvas, duck, or any other similar material and provided with a suitable covering, as hereinafter described, together with a braid or edging which is connected to the fabric of the garment and the lining as also hereinafter described.

As illustrated in these figures, the lower 55 edge of the stiffening member 12 is provided

stitching, as will be understood is subsequently covered and concealed from view by the skirt 15.

- By positioning the edging member so that 5 the same projects appreciably above the edge of the garment, the edging member effectually conceals from view the lining 14 when the latter rides up above the edge of the garment as it frequently does in use. 10 While it is not essential that the edging member be provided with the edge bead, as shown at 19, it should be noted that this bead serves the dual function of concealing the lining member and also of preventing 15 the latter from riding up above the edge of the garment, it being noted that the bead slightly overlies the upper edge of the lining member.

By reference to Fig. 3, it will be seen that 20 instead of making the cover 13 and the lining member 14 in two parts, these may be made of one piece of material by suitably folding the same as indicated at 24; or as shown in Fig. 4 the cover member 13 may be 25 entirely dispensed with and the edge of the lining member as indicated at 25 may be made to come substantially flush with the edge of the stiffening member 12, as indicated at 26. Obviously also, other and equivalent 30 forms of the invention may be used.

By reference to Fig. 5, it will be seen that 35 in carrying out the invention, instead of simultaneously attaching the braid or edging member to the fabric of the garment and to the lining member, the lining may be made to include this braid or edging member by having the same secured thereto by a line of stitching indicated at 27. In this instance as will be understood, the lining 40 with the braid or edging attached thereto is secured to the fabric body of the material in substantially the same way as that hereinbefore described, but with an additional line of stitching which is substantially co- 45 incident with the line of stitching by which the braid or edging member is secured to the lining member, both the lines of stitching being concealed when the parts are secured to the body of the garment and over- 50 turned as hereinbefore described.

In applying the waist band construction shown in Fig. 5 to a garment the line of stitching 27 serves as a guide, and the operator in running the stitching which secures the waist band to the garment should run this last mentioned line of stitching along a line coincident with the stitching 27. When the lining is applied to the garment in this manner and the lining construction over turned, the edging member will project the desired distance above the edge of the garment.

The waist band or lining construction shown in Fig. 5, and shown in Fig. 2 as 60 applied to a garment, and also the modifica- 65

tions shown in Figs. 3 and 4, may be manufactured in large quantities and sold, in roll or other form, as a unitary structure to the manufacturer who is thus saved the tedious and difficult duty of assembling the waist-band sections in applying the waist-band to the trousers or other garment. 70

We claim as our invention:

1. In a garment, an edging and lining construction comprising a stiffening member, a lining member, and an edging member, the said members being connected to the body of the garment and to each other by a line of concealed stitching. 75

2. In a garment, an edging and lining construction comprising a stiffening member, a lining member having a depending skirt, and an edging member, with the said members being connected to the body of a garment by a line of concealed stitching 80 and the said skirt overlying a second line of stitching by which the lining and the stiffening members are also connected to the body of the garment. 85

3. In a garment, an edging braid member, a stiffening member, and a lining member, the said parts being connected to one another by a line of stitching so placed that when the body of the garment is turned over and the said stiffening member and lining 90 are turned over, the line of stitching will be concealed and the edging project an appreciable distance beyond the said over-turned edges, thereby concealing the line of stitching by which the said parts are connected. 95

4. In a garment, an edging braid member, a stiffening member, and a lining member, the said parts being connected to one another by a line of stitching so placed that 100 when the body of the garment is turned over and the said stiffening member and lining are turned over, the line of stitching will be concealed and the edging project an appreciable distance beyond the said over-turned edges, thereby concealing the line of stitching by which the said parts are connected, the said lining member also including a skirt which overlies a second line of stitching by which the stiffening member 110 and a part of the lining are also secured to the body of the garment. 115

5. In a garment, a lining comprising a stiffening member, a lining body overlying one edge of the stiffening member and also 120 looped to provide a skirt at this edge of the stiffening member with these parts connected by a line of stitching and the lining body folded to provide an additional loop to cover the said line of stitching, a braid 125 or edging member placed on the edge of the fabric of the garment with the opposite edges of the stiffening member and lining member placed on the said braid or edging member, a line of stitching connecting the edge 130

- of the garment the braid or edging member and the said overlying edges of the stiffening member and lining member, with the said body of the fabric and the overlying edges 5 to project beyond the edge of a garment and the edge of the lining member when the waistband is secured to the edge of a garment and overturned. 25
- 5 of the stiffening member and body member both overturned to conceal the line of stitching by which these parts are connected, thereby permitting the edging or braid member to protrude appreciably beyond the said 10 30
- 10 overturned edges, and a line of stitching concealed by the loop forming the skirt of the lining member for connecting the said lining member to the body of the garment.
6. As a new article of manufacture, a 15
- 15 composite waistband structure, for application to the trousers material as a unit, comprising a stiffening member, a lining member secured to the stiffening member, and an edging member secured to the outer 20 35
- 20 face of the lining member adjacent the edge of the lining member and in position to project beyond the edge of a garment and the edge of the lining member when the waistband is secured to the edge of a garment and overturned.

Signed by us this 8th day of December, 1919.

MAX PUGATSKY.
ROBT. D. VON RENTSCH.
